UNITED STATES PATENT OFFICE.

EDGAR DUERR, OF BELLA VISTA, ENGLAND.

REVERSIBLE SCREW PROPELLER.

Application filed November 14, 1921. Serial No. 515,063.

To all whom it may concern:

Be it known that I, EDGAR DUERR, a subject of the King of Great Britain and Ireland, and resident of Bella Vista, Langham 5 Road, Bowdon, in the county of Chester, England, have invented certain new and useful Improvements in Reversible Screw Propellers, of which the following is a specification.

10 This invention relates to screw propellers of the type in which the angularity of the propeller blades with relation to the axis of the propeller shaft can be altered to reverse the direction of propulsion of the boat 15 or the like to which the propeller is fitted.

The object of my invention is to provide an improved arrangement of the means for operating the propeller blades which shall be strong, efficient and reliable, shall permit 20 of the blades being turned to any desired position and shall automatically lock the blades in such position.

My invention comprises the combination with each propeller blade of a pinion thereon 25 engaged at opposite points by two pinions keyed to a shaft by keys in right and left hand spiral keyways so that endwise movement of the shaft imparts opposite angular movements to the pinions thereon and so 30 turns the propeller blades to any desired angle.

My invention further comprises the details of construction and arrangement hereinafter described and claimed.

35 Referring to the accompanying sheet of explanatory drawings:—

Figure 1 is a sectional elevation and Figure 2 an end view of a reversible screw propeller constructed and arranged in one convenient form in accordance with my invention.

The same reference letters in the two views indicate the same parts.

In the illustrated application of my invention, the propeller boss is made in three parts, one part *a* being secured upon a hollow driving shaft *b*, a second part *c* which carries the blades *d* and their reversing mechanism and which screws on to the first 50 part, and a third part *e* which is screwed into the second part. The complete boss may be of any desired external form.

Within the hollow shaft *b* before referred to, is disposed a shaft *f* having right and 55 left hand spiral keyways *g* therein, the said central shaft passing through the propeller

boss and carrying two bevel pinions *h*, *i* which have keys engaging said keyways. Each propeller blade *d* has a pinion *j* keyed thereon which is engaged at opposite sides 60 by the two pinions *h*, *i* aforesaid. A rod *f'* connected to the shaft *f* serves to reciprocate and rotate the latter.

With the construction and arrangement before described, when the central shaft *f* 65 is given longitudinal movement, the two pinions *h*, *i* thereon are turned through equal angles in opposite directions and so turn the propeller blades *d*. The latter can be turned to any position from a "feathering" 70 position to one giving full ahead or full astern motion to the boat to which the propeller is fitted. By reason of the arrangement of the two pinions upon the shaft *f*, the propeller blades are self locking in any 75 position and no torque is transmitted to the said shaft.

The drive to the propeller may be arranged through both the hollow and central shafts or through either of these. In the 80 arrangement illustrated, the part *k* is attached to the engine driving shaft or its equivalent and the end of the shaft *b* is keyed therein. The rod *f'* passes through a 85 cross head or disc *m* which is attached to a sliding collar *n* by rods *o*. The latter pass through holes in part *m* and are thereby caused to rotate the cross head *m* and the rod *f'*. A suitable fork or its equivalent operated by hand or by power traverses the 90 collar *n* and the shaft *f* for altering the angular position of the propeller blades.

To give strength to the propeller blades, these are each supported at both sides of the pinion thereon as shown. To place the 95 blades in position they are threaded into the boss through the bevel pinions, the latter being pinned to prevent unscrewing.

The propeller is simple to assemble, readily manipulated for reversing and speed controlling purposes, and the blades are not liable to ready fracture or breakage from the boss or to become jammed during operations. It can be used upon aircraft, as a fan or exhauster and for other purposes. 100

If desired, instead of traversing the shaft *b* from the engine side of the propeller it may be operated from the opposite side and the propeller shaft *b* be made solid. 105

I claim:—

110 1. In reversible screw propellers, the combination with a plurality of blades, a boss

whereon the said blades are pivotally mounted and pinions secured to the blade pivots, of a pair of wheels engaging said pinions and means for imparting rotary movements 5 in opposite directions to said pinions, as set forth.

2. In reversible screw propellers, the combination with a plurality of blades, a boss whereon the said blades are pivotally mounted and pinions secured to the blade pivots,

of a shaft in said boss, a pair of wheels on said shaft engaging said pinions, right and left hand spiral key and keyway connections between said shaft and said wheels, and means for imparting longitudinal movements to said shaft relatively to said wheels, as set forth. 15

In testimony whereof I have signed my name to this specification.

EDGAR DUERR.
